UNITED STATES PATENT OFFICE.

JOHN E. BOYLE, OF SCRANTON, PENNSYLVANIA.

CABLE-TROLLEY.

No. 805,338.

Specification of Letters Patent.

Patented Nov. 21, 1905

Application filed November 12, 1904. Serial No. 232,492.

To all whom it may concern:

Be it known that I, JOHN E. BOYLE, a citizen of the United States, residing at Scranton, in the county of Lackawanna and State of Pennsylvania, have invented certain new and useful Improvements in Cable-Trolleys; and I do hereby declare the following to be a full, clear, and exact description of the invention, such as will enable others skilled in the art to 10 which it appertains to make and use the same.

This invention relates to improvements in supporting-trolleys, and is especially adapted for being hung upon continuous supports—such as wires, rods, bars, or the like—without 15 the necessity of slipping the same over the end of such supports.

The invention consists in certain novel constructions, combinations, and arrangements of parts, as will be hereinafter fully described 20 and specifically claimed.

In the accompanying drawings, Figure 1 is a perspective view of a suspending or supporting trolley, as hung from a wire, a portion of a cable being shown as lying across 25 the trolley-wheel. Fig. 2 is a transverse vertical section through the trolley mechanism, taken on a line with the axis of the trolley-wheel.

In the running of conductors for electrical 30 purposes, and particularly the stringing or suspending from poles or other supports telegraph or telephone wires and cables, it is often necessary to employ an antifriction supporting means, over which the conductors or 35 cables can be drawn. This is especially so in view of the modern practice of incorporating a large number of conductors in a single cable, making the same very heavy and unwieldy. In suspending such conductors 40 or cables it is usual to employ a strong supporting-wire, as 1, which is first secured upon the poles or conductor-supports and drawn taut upon the same. The conductors are arranged next below the supporting-cable and 45 secured thereto at intervals by suspending loops, usually of wire or other suitable material. In practice it is customary to employ a team or other power for drawing the cable from one pole to another and pulling the same 50 from the spool upon which it was originally wound.

The supporting-trolley forming the subject of the present invention is made with a frame 2, preferably constructed of strap or

bar iron. The frame is made usually of a single piece of metal, the bar being bent to form a centrally-depending yoke 3, having parallel sides, while the upper ends are bent to one side in opposite directions and then brought inwardly at their ends, so as to be in alignment with the supporting wire or cable. These ends are then folded or bent to form hooks 4, the said hooks being of sufficient size to receive and rest upon the supporting-cable. Set-screws 5 are employed at the supporting 60 ends of the frame, the said set-screws extending into the hooks, so as to be capable of impinging upon the supporting wire or cable, and thus prevent the trolley-frame from slipping upon the wire or cable or from being accidentally removed therefrom. The hooks at the upper ends of the arms of the frame are made to face in opposite directions, so that the frame can be quickly and easily suspended upon the supporting-cable, it being only necessary to raise the frame and twist it a little at an angle to the supporting-cable, after 65 which the frame is twisted back again into alignment with the supporting wire or cable, so that the hooks may drop into place upon 70 the same. The tightening of the said screws will of course operate to clamp the frame into position upon the wire. In the lower or yoked portion of the frame is mounted an antifriction-roller or trolley-wheel 6, which is preferably of the grooved type, so that the cable in 75 passing over the same will be properly guided in position. A bolt or other shaft 7 is passed through the sides of the frame and through the bearing in the center of the trolley-wheel. 80 Spacing-washers 8 are preferably interposed 85 between the ends of the trolley-wheel and the sides of the frame.

Of course it will be apparent that the frame instead of being made of a single piece of bar- 90 iron bent as shown in the drawings may be constructed of a number of pieces which are suitably connected below the trolley-wheel. It is important that the space above the trolley-wheel be open—that is to say, that there 95 be sufficient room between the hooked ends of the arms to permit the insertion of the cable which is to be drawn over the trolley-wheel and also the insertion of the supporting-wire upon which the device is to be suspended. 100 105

The device described may also be used as a traveling carrier by inverting it upon a support, the trolley-wheel running upon a sup-

porting track, cable, or wire, while the load to be transported is suspended upon the hooks of the frame.

It will be evident that the device can be placed upon a cable and a support at any point without the necessity of threading the same upon the ends of such cable or support.

It will be evident that the diagonal arrangement of the suspending-arms operates to brace the trolley against longitudinal movement with respect to its support.

Having now described my invention, what I claim as new, and desire to secure by Letters Patent, is—

- 15 1. A cable - support comprising a frame made of a single bar bent to form a loop and spread apart at the ends to form inclined supporting and bracing hangers, and a trolley-wheel journaled in said loop.
- 20 2. A cable - support comprising a frame, a trolley - wheel journaled therein, and upwardly and diagonally extending arms at each end of the frame forming supporting-hang-

ers, the diagonal direction of the hangers operating to brace the frame against longitudinal swinging or movement upon the support. 25

3. A cable-support comprising a frame having a loop at the bottom, a trolley-wheel journaled in said loop, upwardly-extending arms, one projecting from each side of the frame 30 and bent to extend diagonally upward from the said frame, hooks formed on the upper ends of said diagonal supports capable of engaging the supporting cable or wire, a clamp-screw for each hook to secure it upon its support, the diagonal arrangement of the arms operating to brace the trolley against movement longitudinally with respect to its support. 35

In testimony whereof I affix my signature in 40 presence of two witnesses.

JOHN E. BOYLE.
